UNITED STATES PATENT OFFICE

WARREN N. HUNTER, OF NEWARK, NEW JERSEY, ASSIGNOR TO MUN-KEE PRODUCTS CORPORATION, OF PASADENA, CALIFORNIA, A CORPORATION OF CALIFORNIA

INK PAD

Application filed July 8, 1930. Serial No. 466,481.

My invention relates to an ink pad.

The present invention is an improvement over the ink pads described in United States Patents, Nos. 1,421,952 and 1,429,354. Said 5 patents relate to an ink pad comprising a resilient base which has a shallow recess on top for the reception of an ink absorbent member. The edges of the ink absorbent member engage the under side of an inwardly extending, horizontal flange. When it is 10 desired to supply ink to the absorbent member it is necessary to remove the absorbent member from beneath said flange in order to supply ink to the lower side of said absorbent member. This operation is 15 inconvenient, and it is the object of the present invention to provide means whereby ink may be supplied to the lower face of the absorbent member without the necessity of having to remove the same from its position.

20 With the above and other objects in view as will appear as the description proceeds my invention consists in the construction and arrangement of parts hereinafter described and claimed.

25 Referring to the drawings which form a part of this specification, I have illustrated an ink pad embodying my invention and in which:

30 Fig. 1 is a perspective view of such an ink pad.

Fig. 2 is a vertical section taken on the line 2—2 of Fig. 1.

Fig. 3 is a detailed view taken on the line 35 3—3 of Fig. 1.

Fig. 4 is a central, vertical section of an ink pad showing a modified form of the ink supplying port.

Fig. 5 is a perspective, fragmentary view 40 showing the ink port disclosed in Fig. 4.

Fig. 6 shows the detailed rear view of the ink port with its valve, with portions of the ink pad being broken away.

45 Referring to the drawings: 1 indicates a resilient base preferably made of rubber provided on its upper face with a flange 2 of inverted L-shape in cross section, which provides a shallow recess 3 for the reception of an absorbent member 4 which may be of any convenient construction but is preferably made

in accordance with the construction disclosed in U. S. Patent 1,421,952. It should be noted that the edges 4' of the absorbent member 4 are positioned under the horizontal portion of the flange 2 and are held in place by said flange. The resilient pad 1 is provided on its upper face in the recess 3 with recesses 5 for the reception of any suitable absorbent material 6 to which ink is supplied as needed, and which material 6 in turn supplies the absorbent member 4 with ink.

The flange 2 is cut away at 7 as shown in Figs. 1 and 3, so that by the insertion of a spout of an oil can 8, indicated in dotted lines in Figs. 1 and 3, ink may be supplied to the top of the base 1 beneath the absorbent member 4 from which the ink will flow to the absorbent material 6.

In place of the cut-away portion 7 I may provide a port consisting of a rubber duct 9 preferably integral with the flange 2, the inner end 9' of the duct 9 projecting, terminating in a flat rubber valve 9² which serves as a check valve to prevent the ink from flowing outwardly through the duct 9.

By providing an ink supplying port in the flange 2 ink may be supplied through the can 8 with a spout as described without the inconvenience of lifting the absorbent member 4 out from its position and engagement with the flange 2.

Various changes may be made by those skilled in the art without departing from the spirit of my invention as claimed.

I claim:

1. An ink pad comprising a base having a recess on top, a horizontal flange projecting inwardly from the upper margin of said recess, an absorbent member arranged within said recess with its edge positioned beneath said horizontal flange, and an ink supplying port in said flange communicating with the under side of said absorbent member.

2. An ink pad comprising a base having a recess on top, a horizontal flange projecting inwardly from the upper margin of said recess, an absorbent member arranged within said recess with its edge positioned beneath said horizontal flange, and an ink supplying port in said flange communicating

with the under side of said absorbent member, said ink supplying port being provided with a check valve.

3. An ink pad comprising a resilient base having a recess on top, a horizontal flange projecting inwardly from the upper margin of said recess, an absorbent member arranged within said recess with its edge positioned beneath said horizontal flange, a recess below said absorbent member and absorbent material therein, and an ink supplying port passing through said flange and communicating with the said side of said absorbent member.
- 15 4. An ink pad comprising a resilient base having a recess on top, a horizontal flange projecting inwardly from the upper margin of said recess, an absorbent member arranged within said recess with its edge positioned beneath said horizontal flange, a recess below said absorbent member and absorbent material therein, and an ink supplying port passing through said flange and communicating with the said side of said absorbent member and provided with a check valve.

In testimony whereof I have signed my name to this specification.

WARREN N. HUNTER.
